UNITED STATES PATENT OFFICE.

CHARLES W. DAVIS, OF EDGEWORTH, PENNSYLVANIA, ASSIGNOR TO STANDARD UNDERGROUND CABLE COMPANY, OF PITTSBURGH, PENNSYLVANIA, A CORPORATION OF PENNSYLVANIA.

ELECTRIC FUSE.

1,130,487.

Specification of Letters Patent.

Patented Mar. 2, 1915.

Application filed June 18, 1913. Serial No. 774,430.

To all whom it may concern:

Be it known that I, CHARLES W. DAVIS, residing at Edgeworth, in the county of Allegheny and State of Pennsylvania, a citizen of the United States, have invented or discovered certain new and useful Improvements in Electric Fuses, of which improvement the following is a specification.

My invention relates to fuses adapted to be placed in electric circuits and to interrupt such circuits when the current carried thereby reaches or exceeds a predetermined amount, and has to do particularly with what are known as oil fuses for high tension circuits, such fuses being characterized by the use of a body of liquid, as oil, carbon tetra-chlorid, etc., to dampen out or quench the arc formed upon the blowing of the fusible element.

It is known that the blowing of a fuse in a high tension circuit is attended, particularly when such blowing is caused by a short circuit, with the release of a great amount of energy, which has the effect of a relatively powerful explosion. Even when a short fusible element is used in combination with means for lengthening the gap between the free ends of the conductor, the explosive forces, acting against the relatively unyielding mass of liquid, may be of such intensity as to seriously injure the fuse structure and endanger workmen in the vicinity thereof.

It is the object of my present invention to provide an oil fuse construction whereby a large portion of the energy released upon the blowing of the fusible element may be consumed, thus eliminating to a large extent such prejudicial effects as have been described above.

In the accompanying drawings, which form part of my specification, I have illustrated two embodiments of my invention.

Figure 1 is a vertical sectional view of a junction box, there being two cables entering therein and having their conductors connected by one form of my improved fuse structure, the casing of which is also shown in longitudinal vertical section; Figs. 2 and 3 are sectional views of the fuse casing taken on the lines II-II and III-III, respectively of Fig. 1; Fig. 4 is a vertical sectional

view of a second form of fuse casing; and Fig. 5 is a horizontal sectional view taken on the line V-V, Fig. 4.

55

In the several figures like numerals are used to designate like parts.

In the practice of my invention in its preferred form I inclose the fusible element and the conductor leading thereto within a casing, and I arrange therein a plurality of successive communicating chambers, some being filled with a liquid and others with a compressible gas as air, such chambers being so disposed that the expansive forces 65 must exert their pressure through them, compressing the gas in the gas chambers and moving the liquid in the liquid chambers. The chambers are arranged so that there will be a circuitous path of escape for 70 the expansive forces, thereby adding to the energy-consuming function of the fuse structure. In the preferred form of my invention, I also provide means for widening the gap between the free ends of the conductor after the fusible element has been destroyed; and, in the path of the movable conductor or conductors, I make provision for relatively thin layers of liquid which readily becomes vaporized by the elongated 80 arc as the free end of the conductor passes by or through such layers, thereby consuming a still further part of the energy of the arc. And, in order to assist in breaking down the arc, the partitions which separate 85 the vaporizable layers of liquid are preferably formed of a non-arcing metal.

Referring now to the embodiment of my invention illustrated in Figs. 1, 2 and 3, and first to the general installation shown therein, the cables 1 enter through the bottom of the junction box 2 and are each provided with suitable terminal structures 3 which end in spring clips 4. The fuse casing 5 is preferably cylindrical, open at both ends, 95 and is carried by yokes or brackets 6 of conducting material, provided at their lower ends with knife blade contacts 7, and secured at their upper ends to a suitable handle 8. Extending between and electrically connected to the brackets 6 is a conductor consisting preferably of flexible end portions 9, relatively rigid portions 10 and a central fusible element 11, the casing 5 in-

100

closing the conductor portions 10 and 11. The conductor portions 10 may be provided with suitable abutments 21 which resist the current of liquid as it escapes from the casing 5, and thus cause the conductors to readily move outwardly, widening the gap between their free inner ends. In this embodiment of my invention a relatively large air or gas chamber is formed just above the liquid surrounding or adjacent to the fusible element by means of a supplementary cylindrical casing 12, closed at its upper end, and provided with suitable openings 13, through which the conductor portions 10 extend, and which afford an outlet for the expansive gases. At each side of the casing 12 a plurality of plates 14, preferably formed of non-arcng metal, depend from the upper wall of the casing 5 and form between them chambers 15 and 16, adapted to contain, respectively, relatively thin layers of liquid and gas. Between the outermost plates 14 and the ends of the casing 5 a plurality of plates 17, 17^a, 17^b and 17^c depend from the upper wall of the casing 5; and alternating with these plates there are a plurality of plates 18, 18^a and 18^b extending upwardly from the bottom of the casing. The liquid within the junction box 2 fills the entire lower portion of the casing 5 submerging the conductor portions 10 throughout their full extent, and preferably submerging the fusible element 11. It will be understood, however, that the fusible element may, if desired, be arranged immediately above the liquid. Such liquid also fills the chamber between the plates 17^a and 17^b, there being air chambers or pockets formed between the plates 17 and 17^a, and 17^b and 17^c. As will be readily seen, suitable holes 19 are provided through the upper walls of the casing 5 in order to allow the liquid of the junction box 2 to fill desired chambers between plates 14, and between plates 17^a and 17^b. The edges of plates 17, etc., and 18, etc., preferably extend beyond the general center of the casing 5, and are each provided with a groove 20 so that the conductor may be readily replaced when blown. In operation, when the fusible element 11 blows, the gases, following the line of least resistance, first compress the air within the casing 12, and then exert their pressure through the circuitous passage formed by the successive liquid and gas chambers, compressing the gas in the gas chambers and moving the liquid in the adjoining liquid-filled chambers both in the upper and lower part of the casing. As the liquid is expelled from the end of the casing 5 it strikes the abutments 21 and causes the conductors to move outwardly. However, when the explosive forces are of extraordinary intensity, I find that their action in expanding through the casing 5 will, without the assistance of

the abutments 21, either expel the conductors from the casing or materially widen the gap between their free ends. As the arc is drawn out it vaporizes the relatively thin layers of liquid between the plates 14, and such plates are also effective, by dividing the arc into small lengths, to break it down.

In Figs. 4 and 5 a second form of fuse casing is illustrated. In this form, alternating gas and liquid containing chambers are provided by means of a plurality of concentric cylinders, having holes through which the conductors 10^a, 11^a extend. The central cylinder 22 incloses a body of air immediately above the fusible element 11^a, a tubular body of liquid occupies the space between the cylinder 22 and 23; and air occupies the space between the cylinders 23 and 24 above the conductor portions 10^a. The handle 8^a, only a portion of which is shown, is suitably secured to the top of the casing formed by such cylinders. It will be understood that the structural elements shown in the fuse of Fig. 1 may also be used in this form to adapt it for service in an installation similar to that of Fig. 1. The operation of this second form of fuse will be readily apparent from the above description of the operation of the fuse of Fig. 1.

In the tests which I have made upon my improved form of electrical fuse I find that a very substantial part of the energy released upon the blowing of the fuse is consumed within the fuse casing, and that circuits carrying currents of great strength may be interrupted quietly and without prejudicial explosive effects. Also, I find that the interruption of the circuit takes place rapidly, in most instances within the period of a half cycle of the current which it carries.

I claim as my invention:

1. In an electric fuse installation, the combination with a fuse box provided with a body of arc-dampening liquid, and a pair of electric conductors entering therein; of a fuse structure connecting said conductors and comprising a casing submerged in said liquid and having an expulsion opening, a conductor within the casing provided with a fusible element, and means for providing within said casing between its expulsion opening and said fusible element a plurality of adjoining and communicating liquid-containing and gas-containing compartments.

2. In an electric fuse, adapted when in use to be submerged in a body of arc-dampening liquid, the combination of an elongate open-ended casing, a supplementary casing forming an explosion chamber at the central portion of the elongate casing, a plurality of spaced plates depending from the top of the elongate casing adjacent to each side of the supplementary casing, a plurality of

plates extending alternately from the top and bottom of the elongate casing and between said first mentioned plates and the ends of the elongate casing and forming compartments within the elongate casing, a fluid passage through the upper wall of alternate compartments, and a fuse strip comprising a central low fusion portion within said supplementary casing and high fusion portions exteriorly thereof.

3. In an electric fuse installation, the combination of a junction box, electric cables entering therein, a fuse structure connecting the conductors of said cables and comprising a casing, a conductor within said casing having a fusible element as a part thereof, a plurality of adjoining compartments within said casing arranged successively adjacent to said conductor, a body of arc-dampening liquid within said junction box submerging said fuse casing, and fluid passages through the upper walls of alternate

compartments, the intervening compartments being closed to form air chambers.

4. In an electric fuse installation, the combination of a junction box, electric cables entering therein, a fuse structure connecting an open-ended casing, a conductor within an open-ended casing, a conductor within said casing having a fusible element at the central portion thereof, a plurality of plates extending alternately from the top and bottom of said casing and forming communicating compartments therein, fluid passages through the upper walls of alternate compartments, and a body of arc-dampening fluid within said junction box submerging said casing.

In testimony whereof I have hereunto set my hand.

CHARLES W. DAVIS.
